ANNOUNCEMENT HANDKERCHIEF

Raymond W. Rank, Middletown, Pa.

Application April 3, 1953, Serial No. 24,340

Term of patent 7 years

(Cl. D3—12)

To all whom it may concern:

Be it known that I, Raymond W. Rank, a citizen of the United States, residing at Middletown, in the county of Dauphin and State of Pennsylvania, have invented a new, original, and ornamental Design for an Announcement Handkerchief, of which the following is a specification, reference being had to the accompanying drawing, forming a part hereof.

The figure is a plan view of an announcement handkerchief, showing my new design.

I claim:

The ornamental design for an announcement handkerchief, as shown.

RAYMOND W. RANK.
